CHECK SELECTING APPARATUS

Leslie H. Wadsworth, Magna, Utah, assignor to
The Selector Corporation, Salt Lake City, Utah,
a corporation of Utah

Application October 10, 1932, Serial No. 637,084

3 Claims. (Cl. 194—101)

This invention relates to apparatus for selecting coins or checks, for use in connection with vending machines, coin changing machines or other machines operated or controlled by coins or checks. The function of such apparatus, in general, is to separate proper coins or checks, that is, coins or checks of certain denomination and physical properties, from improper coins or checks, that is, coins or checks differing in denomination or physical properties from said proper coins or checks, for the purpose of preventing fraudulent operation of the vending machine or other apparatus with which the selecting device is associated.

The term "check", as used hereinafter, will be understood to include any coin or check, consisting of metal or other material and capable of causing operation of such vending machines or other apparatus.

The principal object of this invention is to provide an improved form of check selecting apparatus having a plurality of separate selecting chutes adapted for handling checks of different sizes or denominations, and particularly to provide such a multiple-chute selecting apparatus of minimum size, weight and cost.

The invention is particularly applicable to check selecting apparatus of the types described in United States Patents of Wurzbach and Wadsworth Nos. 1,693,104, 1,732,826, 1,756,076, 1,851,557 and 1,907,638 in which the selecting operation is dependent, at least in part on the electrical conductivity of the check, the selection of the checks according to the conductivity thereof being effected by causing the check to traverse a magnetic field which sets up induced electric currents in the check and influences the motion thereof in accordance with the electrical conductivity of the check, and subsequently separating or selecting the checks in accordance with differences in the motion thereof resulting from the influence of said magnetic field.

A particular object of this invention is to provide a multiple-chute check selecting apparatus operating on the above described principle, in which the several selecting chutes are disposed close to one another, preferably side by side in substantially parallel planes, within a compact unitary housing, and in which a single magnet is utilized for maintaining the magnetic fields in all of said chutes, said magnet being provided with a plurality of pairs of pole members magnetized by said magnet and so disposed as to define magnetic gaps across the respective chutes.

When the several chutes are disposed in parallel planes, it is necessary that at least one of the pole members for each chute shall extend through the plane of at least one other chute in order to reach the chute to which said pole member corresponds, and for this reason, it is pre-

ferred that the portions of the respective chutes in which the checks are caused to pass through the magnetic field be off-set with respect to one another, so that the above mentioned extension of the pole members through the plane or planes of the other chute or chutes will not interfere with or affect the movement of the checks in said other chute or chutes.

The individual pole members for the several chutes are preferably adjustably mounted, for movement thereof in a direction substantially perpendicular to the planes of said chutes, for the purpose of accurately aligning the opposing pole faces of said pole members, so as to not only permit accurate alignment of the magnetic gaps therebetween with respect to the corresponding chutes, but to also permit adjustment of the gap length between said pole members.

The accompanying drawings illustrate a form of check selecting apparatus embodying this invention, and referring thereto:

Fig. 1 is a side elevation of such apparatus;

Fig. 2 is an end view thereof, taken from the left end of Fig. 1;

Figs. 3, 4 and 5 are vertical sections on line 25 3—3, 4—4 and 5—5, respectively in Fig. 2;

Fig. 6 is a sectional view on line 6—6 in Fig. 1;

Fig. 7 is a sectional view on line 7—7 in Fig. 1;

Fig. 8 is a transverse vertical section on line 30 8—8 in Fig. 3.

The apparatus is shown as comprising side walls 1 and 2 and one or more intermediate partition walls disposed between said side walls and parallel thereto so as to provide the desired number of selecting chutes therebetween. The particular form of device shown is adapted to handle checks of three different sizes or denominations, such as United States nickels, dimes and quarters. In this case, two intermediate partitions 3 and 4 are provided, and spacing members 5 and 6 are provided at the left and right ends of the apparatus, for spacing apart the walls 1, 3, 4 and 2, to provide three selecting chutes 8a, 8b and 8c therebetween. The width of the respective chutes is preferably only slightly greater than the thickness of the checks which are intended to be handled by the respective chutes. The spacing members 5 and 6 serve to substantially close the ends of said chutes and to form, in conjunction with the side walls 1 and 2, a compact unitary housing.

At the upper portion of said housing are provided openings for insertion of checks into the respective chutes. For this purpose, the side wall 1 is shown as provided with an upward extension 9a having an opening 10a for insertion of quarters into the upper end of chute 8c; the partition member 3 is provided with an upward extension 9b provided with an opening 10b for insertion of nickels into the upper end of chute 8a.

8n, and the partition member 4 and side wall 2 are provided with upward extensions 9d and 11, the former of which is provided with an opening 10d for insertion of dimes into the upper end of chute 8d. The upward extension 9q is cut away as shown at 12, and the upward extension 9n is cut away as shown at 13 so as to permit access to the respective openings 10n and 10d. Suitable spacing members such as indicated at 14 are also provided between the respective upward extensions above mentioned, and said spacing members are so formed as to provide passages 15q, 15n and 15d respectively, for conducting the checks inserted in the respective openings downwardly to a position adjacent the left end of the apparatus. From this point are provided chutes 16q, 16n and 16d, inclined downwardly toward the right end of the housing. Positioned beneath said last named chutes is provided a small permanent magnet 17 of modified horse-shoe shape, whose upper edge portion 18 preferably forms the bottom of the chutes 16q, 16n and 16d. Said magnet may consist of a single magnet extending across all of the selecting chutes and through correspondingly shaped openings in the partition members 3 and 4. The purpose of the magnet 17 is to remove checks or slugs of iron or other metal of relatively high magnetic attractability, and the right ends of the upper and lower portions, which form the two poles of said magnet, are preferably rounded as shown at 19, so as to cause checks attracted thereby to roll downwardly around said poles. The lower face of said magnet is preferably inclined downwardly toward the left as shown at 21.

Spacing strips or plates 22, 23 and 24 are provided in the respective chutes 8q, 8n and 8d, and between the walls 1—3, 3—4 and 4—2 respectively. Below these spacing strips or plates are provided a second set of spacing strips or plates 25, 26 and 27, which are also disposed in the respective chutes and between the respective plates above mentioned. The upper edges of the strips 22, 23 and 24 are inclined downwardly toward the left, so as to provide downwardly inclined passages between said upper edges and the lower face 21 of magnet 17, as indicated at 28q, 28n and 28d respectively, for guiding magnetic checks attracted by magnet 17 back toward the left end of the housing. The right hand edges of the strips 22, 23 and 24 are spaced from the right end spacing members 6 sufficiently to provide passages 29q, 29n and 29d, for downward passage of proper checks, which are not magnetically attracted by magnet 17 to a sufficient extent to remove the same from the path they normally tend to follow. The upper right corners 22', 23' and 24' of the respective spacing strips serve as sharp edged dividing shoulders, so that all checks passing to the right thereof enter the proper check passages 29q, 29d and 29n, while all checks passing to the left thereof enter the improper check passages 28q, 28n and 28d.

The lower faces of the strips 22, 23 and 24 and the upper faces of the strips 25, 26 and 27 are inclined downwardly toward the left so as to provide downwardly inclined passages 31q, 31n, and 31d in the respective chutes, communicating with the lower ends of the corresponding passages 29q et cetera. Furthermore, the strips 22 to 27 inclusive are of such shape and relative disposition that the passages 31q, 31n and 31d are offset with respect to one another, as may be readily seen by a comparison of Figs. 3, 4 and 5 and by the dotted portions shown in Fig. 3.

In the device shown the strips 25, 26 and 27 are disposed at successively lower levels in the order named, and the strips 22, 23 and 24 are of successively greater height in the order named, so that the passages 31q, 31n and 31d in the respective chutes are successively displaced or offset downwardly with respect to one another, but it will be understood that the relative levels of these passages may be reversed or altered, or said passages may be offset with respect to one another in any desired manner. In any case, however, these passages, which constitute the portions of the respective selecting chutes in which the coins are caused to pass through a zone of concentrated magnetic flux, should be offset with respect to one another in the planes of said chutes. The strips 25, 26 and 27 are preferably provided with upper face portions 32, 33 and 34 which are disposed beneath the lower ends of the respective passages 29q, 29n and 29d and are of somewhat less inclination than the remainder of the upper edges of said strips, said face portions 32 et cetera being positioned to receive checks falling through the passages 29q et cetera and cause the same to be brought substantially to rest before starting their downward movement in the respective passages 31q et cetera.

The means for creating zones of magnetic flux across the respective passages 31q et cetera is shown as comprising a horse-shoe magnet 37 whose opposite arms or pole portions 37a and 37b extend at opposite sides of the above described housing. The magnet may extend around or embrace the right end portion of the housing. The respective arms 37a and 37b are provided with pole blocks 38a and 38b respectively. It will be understood that, if desired, these pole blocks may be formed integrally with the respective magnet arms, and it will also be understood that any other suitable type of permanent magnet, or an electromagnet, may be substituted for that shown in the drawings, but in any event said magnet is preferably mounted with the opposite pole portions thereof disposed alongside the opposite sides of the selecting chute housing. In the particular construction shown, the pole blocks 38a and 38b are shown as consisting of separate members abutting the left ends of the respective magnet arms 37a and 37b, the magnet 37 being supported by means of a clamping bracket 39 secured to side wall 1 and provided with clamping screws 41 engaging the arm 37a of said magnet, and the pole blocks 38a and 38b being supported by means of brackets 42 secured to the respective side plates 1 and 2.

The magnet is also provided with a plurality of pairs of pole members 43q—44q, 43n—44n and 43d—44d corresponding to the respective passages 31q et cetera and magnetically connected to the respective pole portions of said magnet. As shown, said pole members are threadedly mounted in bores 45a and 45b in the pole blocks 38a and 38b respectively, and are provided at their outer ends with screw heads 46 for effecting inward and outward adjustment thereof. The pole members 43q et cetera are made of different lengths, so that the respective pairs of pole members define magnetic gaps across the corresponding passages 31q et cetera as indicated at 47q, 47n and 47d respectively. It will be seen that the pole member 44q extends through the planes of chutes 8d and 8n, and through the walls 2, 4, and 3, in order to reach the chute 8q, while the pole member 43q projects only through the wall 1. It will also be seen that, in each of the other

5 pairs of pole members, at least one of the pole members extends through the plane of at least one of the other chutes, in order to reach the chute corresponding to that pair of pole members. However, the offsetting of the respective passages 31q et cetera, as above described, permits the pole members to be arranged in this manner, without interfering with the proper passage of the checks in the respective chutes.

10 The respective members 25, 26 and 27 terminate at a position adjacent the zones of magnetic flux in the corresponding passage 31q et cetera, as shown at 25', 26' and 27', and each of the chutes is provided with an unobstructed space such as indicated at 51q, 51n and 51d, below and to the left of the points 25', 26' and 27', said spaces being sufficiently extended in planes of the respective chutes to permit the checks to fall in a free trajectory through said spaces after leaving the passages 31q et cetera.

15 Impact members 52, 53 and 54 are provided in the respective chutes, and beneath the extended spaces 51q et cetera, and said impact members are provided with impact faces 55q, 55n and 55d, disposed in such position as to be struck only by checks following certain trajectories in falling through said spaces. The chutes are also provided with barrier members 56, 57 and 58 which are preferably provided with sharp pointed upper ends 56', 57' and 58'. The inclination or disposition of impact faces 55q et cetera and the positions of the upper ends 56' et cetera of said barrier members are such that checks striking said impact faces and rebounding therefrom in the proper manner, as determined by the velocity and position of the impact and by the resilience of the checks, will pass over the upper ends of said barrier members and will be delivered through passages 61q, 61n and 61d. These last 20 named passages constitute the passages through which proper checks are delivered to any suitable check controlled vending or dispensing mechanism or other apparatus in connection with which the selecting device is used.

25 Additional passages 62q, 62n and 62d are provided between the impact members 52 et cetera and the barrier members 56 et cetera for conducting away improper checks which fall short of the impact faces 55q et cetera or which fail to rebound from said impact faces sufficiently to pass over the barrier members. The spacing members 5 at the left end of the housing are provided with inclined shoulders 63, 64 and 65. Said spacing members and shoulders are spaced 30 from the left ends of the strips 22, 23 and 24, to provide passages 66q, 66n and 66d, through which checks removed by magnet 17 and delivered through passages 28q et cetera are directed into the improper check passages 62q et cetera. The shoulders 63 et cetera also serve to deflect certain checks which are delivered at excessive velocity from the passages 31q et cetera, into the corresponding improper check passages 62q et cetera. Other passages 67q, 67n and 67d 35 may also be provided, to the left of the impact faces 55q et cetera, for conducting away improper checks which are delivered from the passages 31q et cetera at sufficient velocity to overrun the impact faces 55q et cetera but do not strike the shoulders 63 et cetera. The improper checks delivered through passages 62q, 62n, 62d, 67q, 67n and 67d may be delivered into any suitable receptacle or may be returned to a delivery outlet exteriorly of the vending machine 40 or other apparatus, so that they may be recovered.

by the person by whom they were deposited in the selecting apparatus.

It will be understood that the walls 1, 2, 3 and 4, as well as the spacing strips and plates provided therebetween for defining the check passages of the respective chutes, are preferably made of material of low magnetic permeability, such as brass. It will also be understood that any or all of said parts may be formed integrally with one another, or may be secured together in any suitable manner, as by means of screws or pins, or by brazing.

It is believed that a description of the operation of one of the three selecting chutes will be sufficient to indicate the mode of operation of the others. Referring, for example, to Fig. 4, if a proper check (in the present instance a United States nickel) is inserted through the opening 10n, it will pass downwardly through passages 15n, 16n and 29n, as indicated by the arrows in this figure. Striking the face 33, it will be brought substantially to rest, and will then roll downwardly through passage 31n and through the zone of magnetic flux at 41n, between pole members 43n and 44n. Upon passing through this zone of magnetic flux the check will be retarded just sufficiently, in accordance with the magnetic and electrical properties thereof, to cause the check, after leaving the passage 31n, to fall in some such trajectory as indicated by the arrows and strike impact face 55n. Due to the resilience of the check, it will then rebound from said impact face along some such path as indicated by the arrows, passing over the barrier member 57 and through passage 61n.

35 If an improper check is inserted in this same chute, it will be separated according to one or the other of the following operations, and prevented from entering the proper check outlet passage 61n.

40 A. If a check or slug of iron or other highly paramagnetic material is inserted, it will be attracted by magnet 17 and delivered through passages 28n, 66n and 62n.

B. If a check is inserted which is of greater 45 electrical conductivity than the proper check it will be retarded to a less extent by the magnetic flux at 41n, and will either strike the shoulder 64 and be deflected into the passage 62n or will pass below said shoulder but overrun the impact face 55n and be delivered through passage 61n.

C. If a check is inserted which possesses the proper magnetic and electrical characteristics, as well as weight, so that it is caused to strike the impact face 55n in the proper manner, but is 50 of different resilience than the proper check, it will fail to rebound sufficiently from said impact face and will fall short of the barrier member 57 and be delivered through passage 62n.

D. If a check of improper weight is inserted, it 55 will either fall short of shoulder 23' and pass through passages 28n, 66n and 62n, or will fail to properly strike and rebound from impact face 55n and be discharged through passage 62n or 61n.

60 It will thus be seen that only those checks which possess the proper weight, resilience, and magnetic and electrical properties will be delivered through passage 61n, and all other checks will be delivered through passage 62n or passage 70 67n. In the same manner, the other chutes will operate to deliver only the proper checks, namely, quarters and dimes, through the passages 61q and 61d, and will discharge all other checks through the respective improper check passages.

It will be observed that the individual magnet pole members 43_q et cetera may be adjusted by screwing the same inward or outward in the pole block 38_a or 38_b, as the case may be, so that the faces of said pole members may be brought closer together or further apart, thus regulating the intensity of the magnetic flux therebetween so as to properly adjust the selective action of the magnetic flux in each of the selecting chutes.

10 In the particular form of apparatus above described, the manner in which the magnetic flux is utilized to influence the motion of the check, and the manner in which the subsequent selective separation of the checks is effected in accordance with the motion of the check after it is thus influenced, are similar to the mode of operation of the types of apparatus described in the above-mentioned Patents Nos. 1,693,104 and 1,851,557. In this type of apparatus, the check selecting chute is provided with a downwardly inclined passage in which the check is caused to roll through the zone of magnetic flux, and the check is subsequently delivered from this passage into an extended space in which it is permitted to fall in a free trajectory which is determined by the retarded influence of the magnetic flux the motion of the check, and checks which fall in a certain trajectory are separated from checks falling in other trajectories.

20 30 In the other issued patents above mentioned, other types of apparatus are shown, in which the passing of the check through the magnetic flux, the influencing of the motion thereof by said magnetic flux, and the subsequent separation of the checks in accordance with the motion thereof after being so influenced, are brought about in different ways. It may be noted, however, that in each of these forms of apparatus, the check selecting chute is provided with a passage

35 40 across which a zone of magnetic flux is maintained by means of suitably disposed pole members, the check is caused to pass through said passage and through said zone of magnetic flux in such manner that the velocity or direction of motion of the check is influenced by said flux, and suitable means are provided for subsequently separating checks having a certain motion after being thus influenced from checks having other than this certain motion. By providing a plurality of similar selecting chutes of any of these types, parallel and closely spaced within a unitary housing, the pole members for maintaining the zones of magnetic flux in all of said chutes may be connected to a common magnet in substantially the same manner as above described, provided the portions of the respective chutes in which the checks are passed through the magnetic flux are offset with respect to one another. It will be evident, therefore, that the present invention may be applied to the forms of apparatus shown in any of the above mentioned patents, and the claims appended hereinto are intended to cover any such embodiment of this invention.

55 60 65 I claim:

1. A check selecting apparatus comprising a unitary housing provided with a plurality of check selecting chutes disposed in different parallel planes close to one another within said housing and with openings for insertion of checks into the respective chutes, the respective chutes being pro-

vided with corresponding check-conducting passages offset with respect to one another, a single magnet having its opposite pole portions disposed at opposite sides of said housing and provided with a plurality of pairs of pole members corresponding to the respective chutes, the pole members of each pair being magnetically connected to the respective pole portions of said magnet and having their faces disposed closely adjacent the respective sides of the said offset check-conducting passage of the corresponding chute so as to maintain a zone of magnetic flux across the portion of said passage therebetween and thus influence the motion of a check in passing through said passage, and means associated with the respective chutes to receive checks from said check-conducting passages and operable to selectively separate said checks in accordance with the influence of said magnetic flux upon said motion of the checks.

2. A check selecting apparatus comprising a unitary housing provided with side walls and with a plurality of check selecting chutes disposed in closely spaced parallel planes between said side walls and with openings for insertion of checks into the respective chutes, the respective chutes being provided with corresponding check conducting passages offset with respect to one another, a plurality of pairs of pole members corresponding to the respective chutes and disposed at opposite sides of the respective offset passages thereof, each of said pole members extending through one of the side walls of said housing and across the plane of each chute between said side wall and the chute corresponding to said pole member, a single magnet having its opposite pole portions magnetically connected to the respective pole members of all of said pairs so as to maintain a zone of magnetic flux across said passages in all of said chutes and influence the motion of checks passing therethrough in accordance with the electrical conductivity thereof, and means associated with the respective selecting chutes for selectively separating checks in accordance with the influence thus produced.

3. A check selecting apparatus comprising a plurality of check selecting chutes disposed close to one another in different parallel planes and having openings for the insertion of checks into the respective chutes, the respective chutes being provided with corresponding check-conducting passages offset with respect to one another, a single magnet having its opposite pole portions embracing the outer chutes and provided with a plurality of pairs of pole members corresponding to the respective chutes and arranged in staggered relation, the pole members of each pair being magnetically connected to the respective pole portions of said magnet and having their faces disposed closely adjacent the respective sides of said offset check-conducting passage of the corresponding chute so as to maintain a zone of magnetic flux across the portion of said passage therebetween and thus influence the motion of a check in passing through said passage and means associated with the respective chutes to receive checks from said check-conducting passages and operable to selectively separate said checks in accordance with the influence of said magnetic flux upon the motion of the checks.
